US00D840362S

(12) **United States Design Patent** (10) Patent No.: **US D840,362 S**
(45) Date of Patent: **** Feb. 12, 2019**

(54) **DIMMER SWITCH**

- (71) Applicant: **Lutron Electronics Co., Inc.**,
Coopersburg, PA (US)
- (72) Inventors: **Susan Hakkarainen**, Doylestown, PA
(US); **Jason C. Killo**, Emmaus, PA
(US); **Matthew Philip McDonald**,
Phoenixville, PA (US)
- (73) Assignee: **Lutron Electronics Co., Inc.**,
Coopersburg, PA (US)
- (**) Term: **15 Years**
- (21) Appl. No.: **29/622,607**
- (22) Filed: **Oct. 18, 2017**

(57) **CLAIM**

The ornamental design for a dimmer switch, as shown and
described.

DESCRIPTION

FIG. 1 is a front perspective view of a dimmer switch
showing our new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a front perspective view of a second embodiment
thereof;

FIG. 8 is a front view thereof;

FIG. 9 is a left side view thereof;

FIG. 10 is a right side view thereof;

FIG. 11 is a top view thereof; and,

FIG. 12 is a bottom view thereof.

The dashed broken lines represent structure or features
which form no part of the claimed design; the broken lines
themselves form no part of the claimed design.

1 Claim, 4 Drawing Sheets
